DESIGN FOR A CHISEL

Gustav M. Gunderson, Duluth, Minn.

Application August 13, 1943, Serial No. 110,905

Term of patent 14 years

Cl. D54—13)

To all whom it may concern:

Be it known that I, Gustav M. Gunderson, a citizen of the United States, residing at Duluth, in the county of St. Louis and State of Minnesota, have invented a new, original, and ornamental Design for Chisels, of which the following is a specification, reference being had to the accompanying drawing, forming part thereof.

In the drawing:

Fig. 1 is a top plan view of a chisel showing my new design; Fig. 2 is a side elevational view thereof; Fig. 3 is a bottom plan view; and Fig. 4 is a cross sectional view taken on the line 4—4 Fig. 1.

I claim:

The ornamental design for a chisel, as shown.

GUSTAV M. GUNDERSON.
